DESIGN FOR A COMBINED HAIR BRUSH AND COMB

John Denman Dean, Tolworth, England

Application May 15, 1936, Serial No. 62,667

Term of patent 7 years

To all whom it may concern:

Be it known that I, John Denman Dean, a subject of the King of Great Britain and resident of Tolworth, in the county of Surrey, England, have invented a new, original, and ornamental Design for a Combined Hair-Brush and Comb, of which the following is a specification, reference being had to the accompanying drawing forming part thereof.

I claim:

The ornamental design for a combined hair-brush and comb as shown.

JOHN DENMAN DEAN.
